UNITED STATES PATENT OFFICE.

HENRY B. DURKEE, OF BOSTON, MASSACHUSETTS, ASSIGNOR TO THE UNITED
INJECTOR COMPANY, OF NEW YORK, N. Y., A CORPORATION OF NEW YORK.

COUNTERPOISE ADJUSTING APPARATUS FOR MACHINE TOOL-BEDS AND THE LIKE.

1,121,991.

Specification of Letters Patent. Patented Dec. 22, 1914.

Application filed May 20, 1914. Serial No. 839,862.

To all whom it may concern:

Be it known that I, HENRY B. DURKEE, a citizen of the United States, and resident of Boston, in the county of Suffolk and State of Massachusetts, have invented new and useful Improvements in Counterpoise Adjusting Apparatus for Machine Tool-Beds and the like, of which the following is a specification.

10 My invention relates to adjusting apparatus for machine tool beds and like objects, and is addressed particularly to use with adjustable machine tool beds which are ponderous and moved with difficulty, especially in a vertical direction. I am aware that the effort necessary to operate mechanical lifts for such machine-members has been mitigated by means of counterweights, and that hydraulic means have been employed 15 as the mechanical lift and support for such machine members. But the employment of counterweights involves this detriment, that it relieves the mechanical lift of a considerable part of the weight which the lift supports, and thus detracts from the solidity desired and expected of such machine members when the operations of the machine are performed. The counterweight renders the bed, or what not, a semi "floating" object, 20 whereas when once adjusted it should stand as firm and immovable as possible. Hydraulic lifts and supports are subject to leakage and loss of adjustment and are moreover, hardly adaptable to many situations when 25 a machine bed or the like is to be lifted and supported.

By means of my invention herein described, the work required to raise or lower a machine bed is materially reduced and the 30 mechanical lift relieved of the greater part of the stresses and wear incident to the operations of raising and lowering the bed, while, when the machine bed has been adjusted to the desired position the entire 35 weight of the bed is replaced on the mechanical lift, which by its nature is a solid and unyielding support. Then, when the machine operations are in progress, the machine bed is anchored by its full weight. 40

45 In the drawings hereto annexed, which illustrate my invention,—Figure 1 is a side view of a boring mill with vertically adjustable bed and with my adjusting mechanism attached; and Fig. 2 is an end view

of part of said boring mill, showing the 55 bracket for attaching the counterpoise which forms part of the adjusting mechanism.

The boring mill itself is only shown in part and in outline; A represents the main 60 standard of the boring mill frame, and B its vertically adjustable bed. The boring mill is taken as an example of the machines to which my invention may be applied.

The mechanical lift and support of the 65 bed B is typified by the lifting screws C, which may be mechanically operated in any acceptable manner, as by a worm-shaft, worm-wheels and rotating nuts—none of which are here shown. A rack D is secured 70 to the under side of the bed B, preferably immediately below the center of gravity thereof, and this rack meshes with pinion E, fixed to shaft F. A grooved pulley G, also fixed to shaft F carries a flexible connection 75 H such as a wire rope or cable, which is secured in the groove of pulley G at one end and to the yoke I at the other. Yoke I, side rods J and yoke R, together constitute a side frame, which is mounted to reciprocate 80 with relation to a single acting pneumatic cylinder O, the side rods J being guided for the purpose in holes K and L, formed in ears on the cylinder head M and bracket plate N, respectively. The cylinder O is 85 secured at its open end to the bracket plate N which is apertured at N'. The piston P carries a piston rod Q which is secured to the yoke R. Bracket S which carries the bracket plate N is bolted or otherwise se- 90 cured to the machine bed. A pipe T com- 95 municates with the interior of the cylinder O through the cylinder head M, and leads from some suitable supply of pneumatic pressure, (not shown). In this pipe, placed con- 100 veniently to the hand of the workman, there is a regulating valve U, with its operating handle V. The available pneumatic pressure, the area of the piston P, and the power- 105 multiple of the rack D, pinion E and pulley G, are mutually determined and controlled so that the lifting effort of the pneumatic counterpoise system suffices to relieve the mechanical lift of most, but not all, of the superincumbent load of the bed B, so that 110 when the bed is to be lifted (or lowered) the mechanical lift must be operated. The relief of load, due to the counterpoise system,

makes the operation of the mechanical lift easy (which is particularly desirable when the mechanical lift is worked by hand) and greatly reduces the wear upon the bearings on which the mechanical lift operates. But the necessity for employing the mechanical lift keeps the supporting points for the machine bed always in working position, so that the actual adjustment of the bed is 10 accomplished by elevation or depression of these supporting points. While being lifted or lowered, the machine bed partly "floats" on its supporting points, and is not anchored firmly thereon by the weight of the bed itself. But when the adjustment of the bed is secured, the mechanical lift is stopped, and the workman shuts off the supply of 15 pneumatic pressure by closing the valve U. Thereupon the inevitable slight leakage from the cylinder O causes the full weight of the machine bed to be restored to the bearing points furnished by the now stationary mechanical lift, so that the bed is firmly anchored on its supports, in proper condition 20 for the machine operations.

By employing a single-acting cylinder and the side frame system I, J, R, the leakage of pneumatic pressure which would be involved if a stuffing box were used for the piston Q, is avoided. The flexible connecting member H enables the counterpoise system to be conveniently attached to the machine in a horizontal position.

What I claim and desire to secure by Letters Patent is:

1. In adjusting apparatus for machine tool beds and the like, the combination with the bed of a mechanically operating lift, and a counterpoise comprising a pneumatic cylinder, its piston, connections between the

piston and the bed, and means to control the pneumatic pressure in the cylinder.

2. In adjusting apparatus for machine tool beds and the like, the combination with the bed of a mechanically operating lift, and a counterpoise comprising a pneumatic cylinder, its piston, connections between the piston and the bed, comprising a flexible connecting member, and means to control the pneumatic pressure in the cylinder. 45

3. In adjusting apparatus for machine tool beds and the like, the combination with the bed of a mechanically operating lift, and a counterpoise comprising a single-acting pneumatic cylinder, its piston, connections between the piston and the bed, comprising a side frame connected to the piston, and a flexible connecting member attached to the side frame adjacent to the head end of the cylinder, and means to control the pneumatic pressure in the cylinder. 55

4. In adjusting apparatus for machine tool beds and the like, the combination with the bed of a mechanically operating lift, and a counterpoise, and means to apply and to release the action of the counterpoise on the bed. 60

5. In adjusting apparatus for machine tool beds and the like, the combination with the bed of a mechanically operating lift and a counterpoise effective to counteract only in part the weight of the bed, and means to apply and to release the action of the counterpoise. 70

Signed by me at Boston, Massachusetts, 75 this 19th day of May, 1914.

HENRY B. DURKEE.
